Patented Mar. 14, 1922.

UNITED STATES PATENT OFFICE.

PENROSE H. ZENDT AND ESTELLA S. GARIS, OF SOUDERTON, PENNSYLVANIA.

POCKET.

1,409,809.

Specification of Letters Patent. Patented Mar. 14, 1922.

Application filed July 8, 1920. Serial No. 394,626.

To all whom it may concern:

Be it known that we, PENROSE H. ZENDT and ESTELLA S. GARIS, citizens of the United States, residing at Souderton, in the county 5 of Montgomery and State of Pennsylvania, have invented certain new and useful Improvements in a Pocket, of which the following is a specification.

This invention relates to improvements in 10 pockets for garments and has for its object to provide a safety compartment within and at the back of the main pocket equipped with a closure flap which is stitched or otherwise secured at its ends to the connected side 15 edges of the pocket walls, thereby normally maintaining the flap in closed position, with relation to the mouth or entrance of the safety compartment, to conceal its existence and prevent casual access thereto, as when 20 reaching into the main outer compartment.

A further object is to provide a fastener 25 for the flap arranged to coact with the front or outer wall of the main pocket compartment to prevent access thereto or loss of the contents thereof but which requires an operation entirely separate and independent 30 from the unfastening of the main outer wall, to unfasten the flap and permit access to the safety compartment.

35 With these and other objects in view, the invention consists in certain novel features of construction as hereinafter shown and described and then specifically pointed out in the claim and in the drawings illustrative of the preferred embodiment of the invention.

In the accompanying drawing,

Figure 1 represents a fragmentary elevation of a garment illustrating the invention 40 applied thereto.

Fig. 2 represents a vertical sectional view through the pocket on the line 2—2 of Fig. 1, and,

Fig. 3 represents a horizontal sectional 45 view on the line 3—3 of Fig. 1.

Referring to the drawing in detail, wherein similar reference numerals designate corresponding parts throughout the several views, the numeral 5 indicates a fragment 50 of a garment having the usual opening or slit 6 therein forming the mouth or entrance to a pocket.

The improved pocket forming the subject matter of the present invention consists 55 of the front or outer wall 7 which lies against the inner surface of the fabric 5

below the slit or opening 6 therein, the intermediate wall 8 and the rear or inner wall 9. The edges of the walls at the bottom of the pocket and at the sides thereof 60 are connected by stitching or other means to provide the outer or main compartment 10 and the inner safety compartment 11 both of which open in the same direction and the mouths or entrances thereof are disposed in contiguous relation.

The top edge of the intermediate wall or partition 8 preferably lies below the slit or opening 6 and is normally engaged and closed by an overlying flap 12 which is secured to or forward integral with the top edge of the slit 6. The flap 12 extends downwardly a distance below the top edge of the intermediate wall 8 and into the compartment 10 and is stitched or otherwise secured at its ends between the connected side edges of the several walls 7, 8 and 9, as indicated at 13 whereby the flap is normally maintained in a predetermined position overlying the top portion of the intermediate wall 8 and closing the entrance to the compartment 11.

A button 14 is sewed or otherwise secured to the central portion of the top edge of the intermediate wall 8 and is disposed to 85 enter a hole 15 formed in the contiguous portion of the flap 12 whereby the latter may be readily and secured fastened in closed position. The contiguous portions of the front wall 7 of the pocket and the fabric 5 are 90 also provided with openings 16 for receiving the button 14 whereby the main compartment of the pocket is closed and loss of the contents thereof prevented.

From the foregoing it is clearly evident 95 that I have provided an improved pocket equipped with a safety compartment which is effectively concealed from the casual observer and is effectively guarded against unauthorized entry by the engagement of 100 the flap 12. Furthermore, it is evident that by connecting the terminals 13 of the flap 12 with the sides of the pocket, the flap is normally maintained in proper overlapping 105 relation to the edge of the intermediate wall 8. When it is desired to obtain access to the inner safety compartment 11, the flap 12 is disengaged from the button 14 and is pulled upwardly as suggested in dotted lines in Figs. 1 and 2, whereupon the top part 110 of the intermediate wall 8 may be moved outwardly against the inner surface of the

outer or front wall 7, as also suggested in dotted lines in Fig. 2, to permit convenient entrance to the compartment 7. When neither of the compartments is in use, the 5 button 14 is passed through both openings 15 and 16 and effectively closes both compartments preventing loss of the contents thereof or possibility of theft thereof.

What we claim is:

- 10 The combination with the wall of a garment having a slotted opening therein, the adjacent edges of the slotted opening having overlapping free edge portions, of a double pocket structure comprising a front, 15 an intermediate and a rear wall dependingly supported from said slotted opening, the front wall of said pocket being secured to the inner face of the lower portion of the garment wall and having its top edge em-

braced by the free edge of the latter, the 20 rear wall of said pocket extending upwardly and secured to the rear face of the upper portion of the garment wall on a line above the free edge of the latter, the free edge portion of the upper wall portion of the garment depending between the intermediate wall and the front wall of said pocket, and fastening means carried on the intermediate wall of said pocket and engageable with the 25 depending edge portion of the upper wall portion of the garment and with the embraced edge portion of the front wall of said pocket.

In testimony whereof, we affix our signatures hereto.

PENROSE H. ZENDT.
ESTELLA S. GARIS.
